US0D1027922S

(12) **United States Design Patent** (10) **Patent No.:** **US D1,027,922 S**
(45) **Date of Patent:** **** May 21, 2024**

(54) **CASE FOR MEDIA PLAYER**

(71) Applicant: **Yoto Limited**, London (GB)

(72) Inventors: **Thomas Ashley Ballhatchet**, London (GB); **Jonathan Marshall**, London (GB); **Eun hak Lee**, London (GB); **Guy Naor**, London (GB)

(73) Assignee: **Yoto Limited**, London (GB)

(**) Term: **15 Years**

(21) Appl. No.: **29/833,461**

(22) Filed: **Apr. 4, 2022**

(30) **Foreign Application Priority Data**

Oct. 5, 2021 (GB) 6168548

(57) **CLAIM**

The ornamental design for a case for a media player, as shown and described.

DESCRIPTION

FIG. 1 is a first isometric view of a case for media player incorporating my new design;

FIG. 2 is a front elevation view thereof;

FIG. 3 rear elevation view thereof;

FIG. 4 is a first side elevation view thereof;

FIG. 5 is a second side elevation view thereof;

FIG. 6 is a top plan view thereof;

FIG. 7 is a bottom plan view thereof; and,

FIG. 8 is a second isometric view shown in use with environment.

The broken lines shown in the drawings illustrate portions of the case for a media player and environment, and form no part of the claimed design.

1 Claim, 8 Drawing Sheets
